UNITED STATES PATENT OFFICE.

LEE STURGES, OF CHICAGO, ILLINOIS, ASSIGNOR TO SOLAR-STURGES MANUFACTURING CO., A CORPORATION OF ILLINOIS.

COMBINATION AGITATOR AND SAMPLER.

Application filed December 27, 1921. Serial No. 525,052.

To all whom it may concern:

Be it known that I, LEE STURGES, a citizen of the United States, and a resident of the city of Chicago, in the county of Cook and State of Illinois, have invented certain new and useful Improvements in a Combination Agitator and Sampler; and I do hereby declare that the following is a full, clear, and exact description of the same, 10 reference being had to the accompanying drawings, and to the numerals of reference marked thereon, which form a part of this specification.

This invention relates to a combination agitator and sampler which is particularly adapted for agitating a mass of fluid to make the same homogeneous and for removing a portion of the fluid subsequent to such agitation for purposes of sampling.

Heretofore the general practice in operations of this kind has involved the use of two implements or utensils, one for agitating the fluid and one for removing the same from the container, and it is an object of 25 the present invention to provide a single means for performing both functions and thereby reducing the time consumed.

It is also an important object of this invention to provide a combination agitator and sampler which is provided with apertures to facilitate agitation, and with means to facilitate the pouring of the agitated fluid from the sampler.

It is an important object of this invention 35 to provide a device of the kind described which may be conveniently used to agitate a fluid and remove a portion thereof from a container and which at the same time is simple in construction and may be easily cleaned.

Other and further important objects of this invention will be apparent from the disclosures in the specification and the accompanying drawings.

The invention (in a preferred form) is 45 illustrated in the drawings and hereinafter more fully described.

On the drawings:

Figure 1 is a top plan view of a combined 50 agitator and sampler embodying the principles of this invention.

Figure 2 is a fragmentary section on the line 2-2 of Figure 1 with parts in elevation.

Figure 3 is a fragmentary section on the

line 3-3 of Figure 1 with parts in elevation.

Figure 4 is a top plan view of a slightly modified form of agitator and sampler showing the handle in section. 60

Figure 5 is a fragmentary section on the line 5-5 of Figure 4 with parts in elevation.

As shown on the drawings:

The device of this invention is preferably 65 constructed of stamped metal and comprises a shallow concave member 1 which is provided with an integral flat flange 2 having an upwardly extending lip 3 thereon. The flange 2 is provided with a plurality of 70 apertures 4 which allow the fluid to pass therethrough during the process of agitation. In order that fluid may be poured from the concave member 1 a spout or channel is provided which leads from said member through the flange 2 to an opening in the lip 3, this spout or channel being best 75 illustrated in Figures 1 and 3 and indicated in said figures by the reference numeral 5. The center of the concave member 1 is 80 formed inwardly as indicated at 6, and engaged through an aperture in said inwardly formed portion is a reduced portion 7 of a handle 8 which extends upwardly therefrom and is preferably provided with a 85 loop 9 whereby it may be conveniently grasped by the operator. Engaged around the reduced portion 7 and mounted in the recess afforded by the inwardly formed portion 6 of the member 1 is a washer or gasket 10 which is held in position by riveting the reduced portion 7 at 11, and engaged around said reduced portion between the floor of the member 1 and the handle 8 is a 90 similar washer or gasket 12. 95

A slightly modified form of combined agitator and sampler is shown in Figures 4 and 5 wherein the member 1 is replaced by a somewhat deeper member 13 and wherein the lip 3 is made slightly higher as indicated 100 at 14. In this construction the inwardly formed portion 6 is omitted and the reduced portion 7 of the handle 8 is engaged through the flat bottom of the member 13 having washers or gaskets 15 and 16 engaged therearound on the inside and outside of said member respectively. 105

This form of device is particularly adapted for use where it is desired to remove larger quantities of fluid. 110

It will accordingly be observed that this invention provides a utensil which may be conveniently used for agitating a fluid and removing a portion of the same for sampling or other purposes subsequent to such agitation. The device is particularly adapted for use in testing milk and determining the amount of butter fat contained therein, in which case the agitator is first employed to thoroughly mix the cream with the milk, after which a small portion of the mixed fluid is removed in the concave member 1 or 13 and is poured outwardly into the testing apparatus through the spout or channel 5. By having the implements or utensils necessary to effect these operations combined in a single device, it is possible for an operator to work much more rapidly, and since samples are ordinarily taken from each container it is of course apparent that such rapidity is desirable.

The device may be economically manufactured and on account of the fact that there are no sharp angles or corners it may be easily kept clean.

I am aware that numerous details of construction may be varied though a wide range without departing from the principles of this invention, and I therefore do not pur- pose limiting the patent granted otherwise than necessitated by the prior art.

I claim as my invention:

1. A device of the class described comprising a shallow concave utensil, an apertured integral flange thereon, a spout leading from the utensil to the edge of the flange, and a handle secured to the utensil.

2. A device of the class described comprising a shallow concave member having a peripheral lip, apertures in the member near the periphery thereof, and a chamber formed in the member extending from the center thereof through the lip.

3. A device of the class described comprising a shallow concave member, a plane portion integral therewith, apertures in the

plane portion, an upwardly extending lip on the outer edge of said plane portion, and a pouring channel formed in said concave member; plane portion and lip. 50

4. A device of the kind described comprising a shallow concave member, apertures formed in the member near the periphery thereof, means formed in the member whereby fluid may be poured therefrom, and a handle secured to the center of the member and extending upwardly therefrom. 55

5. A device of the kind described comprising a shallow concave member, apertures formed in the member near the periphery thereof, an inwardly formed portion at the center of said concave member, a handle extending through said inwardly formed portion, and securing means for the handle placed in said inwardly formed portion and flush with the bottom of said concave member. 60

6. The combination with an agitator member having a plurality of apertures thereon, of a dipping member integral therewith, and a handle secured to said dipping member whereby the combination may be used to agitate a liquid and to dip up a portion thereof without requiring the operator to relinquish one implement and take another. 70

7. A combined agitator and sampler comprising a plate and a handle extending upward therefrom, said plate including a dish-shaped middle part, a flat annular flange surrounding said dish-shaped part and having perforations and an upturned lip, said plate being provided with a depressed groove forming a pouring spout extending from the dish-shaped part across the flat flange and though said lip. 75

In testimony whereof I have hereunto subscribed my name in the presence of two sub-scribing witnesses.

LEE STURGES.
